DESIGN FOR A TEXTILE FABRIC

Leo Schwartzberg, New York, N. Y.

Application January 13, 1941, Serial No. 98,015

Term of patent 3½ years

To all whom it may concern:

Be it known that I, Leo Schwartzberg, a citizen of the United States, residing in New York city, in the county of New York and State of New York, have invented a new, original, and ornamental Design for a Textile Fabric, of which the following is a specification, reference being had to the accompanying drawing, forming part thereof.

Fig. 1 is a plan view of a textile fabric showing my new design, and

Fig. 2 is the reverse side of a portion thereof.

I claim:

The ornamental design for a textile fabric, substantially as shown.

LEO SCHWARTZBERG.
